Wm. Smith, Landfield, Mass.

Collector's Patent.

The article referred to in these Letters Patent, and making part of the same, containing a description in the words of the said Wm. Smith himself of his improvement in baking sugar.

To all to whom these presents shall come.

Be it known that I, Wm. Smith of Landfield in the County of Berkshire & State of Massachusetts, have invented a new & useful improvement in the baking of sugar, and that the following is a full & exact description of the construction & operation of the said machine as invented or improved by me.

The machine or moulds are casted in a square or frame of equal or unequal sides, & may be constructed either of metal or wood with or without bottoms attached to them & are divided into apartments by partitions or spines each other at right angles. The size of the apartments may be varied to correspond with the weight of the cakes desired to be produced. The under sides of the partitions are to be made thicker than the upper, that the cakes may more readily drop from the moulds when turned bottom uppermost.

The moulds when used may be moistened with oil or water to prevent the sugar from adhering to them.

If the moulds are used without bottoms attached a damp cloth may be spread on a smooth level surface upon which place the moulds and confine them at first the corners of the frame by the hands or otherwise so that by turning them the moulds may be confined & released at pleasure.

The sugar when in a proper state for baking is turned into the moulds & the apartments filled, when entirely watered & retain an impression may be stamped with such figures

388.

figure was cleaned; when sufficiently hard by cooling the molasses taken up, turned over & cleaned of the scales and then put into water to melt off the sugar if any adheres to them.
